UNITED STATES PATENT OFFICE

THOMAS W. TANSLEY, OF NEW YORK, N. Y., ASSIGNOR TO BLOCH FRERES, INC., OF NEW YORK, N. Y., A CORPORATION OF NEW YORK

DESIGN FOR A HANDKERCHIEF

Application filed February 6, 1933. Serial No. 47,131. Term of patent 3½ years.

To all whom it may concern:

Be it known that I, THOMAS W. TANSLEY, a citizen of the United States, and resident of the city of New York, in the county of New York and State of New York, whose post-office address is 28 East 31st Street, city of New York, county of New York, and State of New York, have invented a new, original, and ornamental Design for a Handkerchief, of which the following is a specification, reference being had to the accompanying drawing, forming part thereof.

The figure is a plan view of a handkerchief showing my new design.

I claim:

The ornamental design for a handkerchief substantially as shown.

THOMAS W. TANSLEY.
